(57) **CLAIM**

The ornamental design for a tire, as shown and described.

DESCRIPTION

FIG. 1 is a side perspective view of my new tire;
FIG. 2 is a front elevational view of my new tire of FIG. 1;
and,

FIG. 3 is a side elevational view of my new tire of FIG. 1,
the opposite side view being a mirror image thereof.
The claim comprises only the tire tread and shoulder surfaces,
as shown in solid lines in the drawings. The broken
line showing of a tire sidewall and inner bead depicts
environment and forms no part of the claim.
